UNITED STATES PATENT OFFICE

KILIAEN M. VAN RENNSELAER, OF WOODMEER, AND HUGO E. SWANSON, OF BROOKLYN, NEW YORK, ASSIGNEES TO TRIANGLE KAPOK MACHINE CORPORATION, OF BROOKLYN, NEW YORK, A CORPORATION OF DELAWARE

APPARATUS FOR TREATING FIBERS AND THE LIKE

Application filed October 22, 1929. Serial No. 401,584.

This invention relates in general to apparatus and its associated system for treating fibers, linters and the like.

One of the objects of this invention is the provision of a new form of construction in a chamber for receiving dust or particle laden air.

A further object of this invention is the provision in a container of this type of construction which permits ready escape of the air after delivery thereto and the complete capture of the particles carried thereby.

A further object of this invention is the provision of an aeration tank and piping system including means for removing the dust from the material being treated, suction boxes, blowers, beaters and the delivery nozzles.

A further object of this invention is the provision of a new form of aeration tank having a section in the bottom thereof, a connection for delivering the material thereto, a rotating beater in the bottom thereof above the section, and a delivery passage therefrom.

A further object of this invention is the provision of means connected to the aeration tank below the section, for removing the dust and dirt therefrom and delivering it to a suitable receptacle.

A still further object of this invention is the provision of the delivery passage from the aeration tank of means for removing any dust and dirt carried by the material being treated as it leaves the aeration tank.

Another object of the invention is the provision of a feed hopper in said means.

An additional object of this invention is the provision of a novel form of suction box construction in the conduit system comprising the closed circulatory system connected to the aeration tank.

These and other objects as will appear from the following disclosure are successfully secured by means of this invention.

This invention resides substantially in the combination, construction, arrangement and relative location of parts, all as will be described in greater detail below.

Referring to the drawings—

Figure 1 and 1a taken together show the

complete system of this invention with some parts broken away;

Figs. 2 and 2a represent together a top plan view of the device in one part and a cross sectional view taken on the line 2—2 of Fig. 1 in the other part; 55

Fig. 3 is a perspective view of the interior of the dirt and particle removing means;

Fig. 4 is an enlarged detail view of the suction boxes and their association with the conduit system, showing some parts in cross section; 60

Fig. 5 is a cross sectional view taken on the line 5—5 of Fig. 4.

This invention will be described in connection with the treatment of fibers, cotton linters and similar substances used for filling mattresses and the like. The invention of course in its broadest aspect is not limited to this field of use, but is described in connection therewith for purpose of illustration.

In general the invention has to do with improvements in a continuous circulatory system for cleaning and breaking up the more or less dirty compacted fibers before they are in condition for use in filling mattresses and the like. The invention involves a number of improvements in such a system which will be more readily understood by detail reference to the drawings, at which time the function and operation of the various elements will be described in detail. 70 75 80

In connection with a system of this type the receptacle which receives the dirt and dust laden air is called the dust house. We wish to particularly emphasize the fact however that in its broadest aspect the dust house in the improved form shown may be considered as a receptacle for receiving any particle laden air in which the particles may be removed from the air and the air discharged therefrom. The usual purpose as now employed is known as a cyclone. However, with this invention the particles may be removed from the air and captured within the container and the air permitted to escape without the use of a cyclone. As one example of the broad aspect in this feature of the invention it may be pointed out that the receptacle constructed in accordance with the principles 90 95 100

of this invention may be used for instance as a grain bin and the grain delivered thereto by currents of air. The grain is captured within the receptacle and the air permitted 5 to escape. It is shown as comprising a framework of any suitable construction and form, made up of the beams 1 which are fully enclosed or covered on the outside by the covering material 2 which may be, for example, 10 metal. In one form this construction would comprise a completely enclosed container. The interior of the container is covered with burlap or any suitable porous material which overlies the beams 1 and completely lines the 15 interior of the container. The closeness of the weave of the material will depend upon how small the particles are within the dust laden air. If the particles are grain, for example, the material 3 might easily be a fine 20 mesh wire screen. The walls 2 are provided with windows or ventilators 4 near the top and bottom of as many sides as is necessary to permit the free and easy escape of the air. The particles carried into the bin by the air 25 will be trapped therein and may be removed from the top 5. In connection with the present use of the device it will be called a dust house.

Delivering into the dust house is a pipe 6 30 connected to the discharge nozzle of a blower 7. A pipe 8 connects to the intake port of the blower and is connected through a suitable gate valve 9 to the aeration tank 10 below the section 16. The aeration tank 10 is 35 provided with a pipe 11 connected thereto, which is closed off at the point of connection by means of a thin wall 12, which is of weaker material than the walls of the tank, so that if undue pressure is created therein the wall 12 40 will be destroyed and the pressure relieved through the pipe 11. The tank 10 is provided with chamber 11 at the bottom thereof in which is rotatably supported on the shaft 14 a series of paddles 15 which are intended to 45 rotate in a clockwise direction. The space below the section 16 may be reached through a door 17. A discharge pipe 18 is connected to the chamber 13 and delivers into a closed chamber, which is provided with a door 20 50 which opens upon the feed hopper 21. The material is introduced into the circulatory system through the hopper 21 and is picked up by the air flowing through the pipe 18 and chamber 19. The lower part of the delivery pipe 18 is provided with a wall 22 which extends upwardly and terminates short of a horizontal wall 24 which is provided with a short vertical fin 25. An extension strip 23 is secured to the wall 22 and may be 55 adjusted with respect to the fin 25 to vary the width of the space between it and the wall 22. The chamber is provided with a door 26 to give access to the interior thereof and with an air inlet as clearly shown in Fig. 3.

60 A pipe 27 is connected to chamber 19 as

shown in the drawings and extends to a point in which a two-way valve 28 is provided as shown in Fig. 1a. At this point a branch pipe 29 is connected to the pipe 27 and as shown in Fig. 2a, when valve 28 is in one position the air and material flows to pipe 29 and when in the other position flows on through pipe 27 shown by dotted lines in Fig. 2a. Pipe 27 which is connected to pipe 34 is provided with a two-way valve 35 which 70 in one position connects it directly to pipe 34 and in the other position closes it off. The portion of pipe 27 shown in dotted lines Fig. 2a provides a direct connection from chamber 19 to the intake pipe 34 of blower 36. Pipe 29 when the valves 28 and 35 are in the proper position receives the air and material 75 and delivers it through the cleaning arrangement to the intake 34.

The section 29 of the pipe is associated 80 with the suction boxes 30 which are provided with doors 31 to permit access to the interior thereof. The bottom portion of pipe 29 within the suction boxes is perforated or enclosed by a section 32, as is clearly shown in 85 Figs. 2a and 5. A series of baffle walls 33 are provided within the suction box and partially encircle the bottom of pipe 39 as is clear from these figures. The intake passage 90 of the blower 36 is also provided with another pipe 37 which connects to the suction box 30 near the bottom thereof as shown in Fig. 1a. This pipe is provided with a suitable valve 38.

The discharge nozzle of the blower is connected to pipe 42. The blower is driven by 95 means of the motor device 41 and the belt connection 40. Pipe 42 is provided with a nozzle 43 to which the mattress or other article to be filled is connected. Pipe 42 is also provided with a branch 44 which connects to the top 48 of the aeration tank. At the point 100 of connection of pipes 42 and 44 is provided a two-way valve which is operated by the lever 44' against the action of spring 45 when the treadle 46 is operated at the connection 47. In the normal position of this valve as 105 shown in Fig. 1 the nozzle 43 is disconnected from pipe 42 which itself is connected to pipe 44. In the path of the air delivered to 110 the tank from pipe 44 is provided a baffle wall in the form of a section 49 and a plate 50.

A pipe 54 discharging into the dust house is connected through the flexible canvas pipe 53 to the nozzle 43 for a purpose to be described later. The motive device is connected by belt 51 to shaft 14. The blower 7 is also connected to shaft 14 through a belt 52.

A description of the operation of the apparatus will now be given. When materials 125 are being treated, blower 7 is operating, paddles 15 are rotating in a clockwise direction and blower 36 is operating. If the suction boxes are being used the section of pipe 27 between valves 28 and 35 is closed off so 130

that the air and material flows through pipe 29. Valve 38 is open sufficiently to create the proper suction in the suction boxes and valve 9 is open to create the proper suction 5 in the bottom of chamber 13. The valve operated by lever 44' is in a position to close off nozzle 43. The door 20 of chamber 19 is open and the material to be treated is delivered into hopper 21 and caught up by the 10 flow of air current in the direction of the arrows shown. Material travels through pipe 27 to pipe 29 and as it flows over the section 32 some of the dust and dirt is removed therefrom. This is due to the suction action of 15 blower 36 through pipe 37. The baffles 33 are provided so that the suction action is not too strong and directed upon the section 32 since if it is, the material will stick to the section and clog it. The material then flows on 20 through the blower and back by the pipe 42 to pipe 44 into the aeration tank, striking the baffle walls 49 and 50. The material falls down and strikes the paddles 15. Here it is broken up and disintegrated from a compacted condition. At the same time the dust, 25 dirt and lighter particles are drawn through section 16 and delivered by blower 7 to the dust house through pipe 6. The main body of material passes through pipe 18 to chamber 19 up along wall 22 and into pipe 27. At 30 this point the elements in chamber 19 will be further described with regard to their operation.

Although a great deal of the foreign material is removed in the aeration tank some of the lighter particles get over into pipe 18. This action is enhanced by the fact that the paddles 15 rotate in a clockwise direction tending to strike the falling material and direct it upwardly and to the right. Some of the lighter particles travel with the material into pipe 18 where they settle on wall 22. The movement of the air into pipe 27 causes them to slide along wall 22 where they finally fall off through the small space between the extension 23 and the fin 25. It will be noted that wall 24 passes a little to the left of the end of the wall 22 so that these particles are not carried along by the air into pipe 27, but 45 are trapped or diverted by the opening between these walls and hence fall down into the space below them. The material is thus circulated through the circulatory system until in a fluffy condition and properly cleaned. 50 A mattress or other casing to be filled is connected to nozzle 43 and a treadle 46 is depressed. This closes off pipe 44 and delivers the material through the nozzle into the casing. When properly filled the treadle 46 is freed and the spring 45 operates the valve to prevent any more material being delivered 55 to the nozzle.

When it is desired not to pass the material through the suction boxes, valves 28 and 35 60 are operated into position to close off pipe 29

and the material then flows on through the section of pipe 27 shown in dotted lines in Fig 2a into pipe 34 and thence through the blower to pipe 42.

When it is desired to clean the dust from the dust boxes pipe 54 is connected to the nozzle 43 as shown in Fig. 2 by means of the flexible canvas connection 53. Valve 38 is opened, valve 35 is rotated so that pipe 27 is closed and valve 28 is moved so that the left hand end of pipe 29 is closed, blower 30 is started, door 31 on the suction box may be partially open or a similar door at the left hand end thereof open. The suction action of the blower 36 draws out the dust and dirt from the suction box and delivers it through pipe 42 to nozzle 43. Treadle 46 is depressed so that the nozzle 43 is opened to pipe 42. The dust and dirt is then blown through the nozzle to pipe 54 and thence to the dust house. If there is any dirt within pipe 29 on section 32 it will be sucked through into the suction boxes and removed.

As emphasized before one of the important features of this invention is the construction of the dust house which has been described in detail above. Other important features are the construction of the aeration tank with the paddles in the bottom thereof, the construction of the suction boxes and the way they are used and the means comprising the chamber 19 and its parts for removing the finer particles of dirt and dust from the materials being treated. It has been found in actual use that this separator as it may be called is very efficient in removing dust and dirt from the material. This dust and dirt slides along wall 22 and is dropped or by-passed through the small passage between walls 22 and 24. The fin 25 acts to prevent the fibers from going through this passage.

From the above disclosure it will be apparent that we have embodied certain principles of construction and operation in a new form of apparatus. These principles have been illustrated in connection with one physical form of device, but we are well aware that those skilled in the art will readily appreciate variations in the physical form disclosed without departing from these principles. We do not, therefore, desire to be strictly limited to the disclosure as given for purpose of description, but rather to the scope of the appended claims.

What we seek to secure by United States Letters Patent is:

1. In a fiber treating apparatus of the type described the combination comprising an aeration tank, a rotatable paddle in the base of the tank, a closed circulatory pipe system connecting the base of the tank with the top, means in the pipe system for causing air to circulate therethrough so as to be delivered into the top of the tank and removed from the bottom, a screen in the aeration tank

below the paddles and suction means connected to the aeration tank below the screen for removing the dust and dirt therefrom.

2. In a fiber treating apparatus of the type described the combination comprising an aeration tank, a rotatable paddle in the base of the tank, a closed circulatory pipe system connecting the base of the tank with the top, means in the pipe system for causing air to circulate therethrough so as to be delivered into the top of the tank and removed from the bottom, a screen in the aeration tank below the paddles, a dust house, and means connecting the aeration tank below the screen with the dust house for removing dust and dirt from the base of the aeration tank to the dust house.

3. In a material treating machine of the type described the combination comprising the closed aeration tank, a rotatable beater mounted in said tank, a closed circulatory pipe system connected at one end to the top of the tank and at the other end adjacent the beater, means in said system for causing an air current to flow through said pipe system and means in said pipe system adjacent the aeration tank for receiving the material as it is delivered from the beaters and for removing dust and dirt therefrom.

4. In a material treating machine of the type described the combination comprising the closed aeration tank, a rotatable beater mounted in said tank, a closed circulatory pipe system connected at one end to the top of the tank and at the other end adjacent the beater, means in said system for causing an air current to flow through said pipe system, means in said pipe system adjacent the aeration tank for receiving the material as it is delivered from the beaters and for removing dust and dirt therefrom, and additional means in the pipe system comprising closed boxes through which a portion of the pipe of the circulatory system passes, said portion being apertured at the part exposed to the interior of the boxes.

In testimony we have hereunto set our hands on this 15th day of October, A. D. 1929.

50 KILIAEN M. VAN RENNSELAER.
HUGO R. SWANSON.
